UNITED STATES PATENT OFFICE.

HERMAN MARCUS, OF BROOKLYN, NEW YORK.

DESIGN FOR A LACE-PIN.

SPECIFICATION forming part of Design No. 14,583, dated January 29, 1884.

Application filed November 8, 1883. Term of patent 7 years.

To all whom it may concern:

Be it known that I, HERMAN MARCUS, of Brooklyn, in the county of Kings and State of New York, have invented and produced a new and original Design for Lace-Pins, of which the following is a full, clear, and exact description.

Reference is to be had to the accompanying drawing, forming a part of this specification, to and which is a front view of my newly-designed lace-pin.

The leading feature of my design consists of a shepherd's crook and a star.

A represents a shepherd's crook, which may

be made to represent a branch of a tree in its natural state.

The crook A is ornamented with a star B, which is placed upon the said crook at the center, and is ornamented as shown.

I claim—

The design for a lace-pin herein shown and described, the same consisting of the shepherd's crook made to represent the branch of a tree, and having fixed to its central face a star, as set forth.

Witnesses: HERMAN MARCUS,
JAMES T. GRAHAM,
EDGAR TATE.
